SAFETY CONNECTION

John D. McClintock, Philadelphia, Pa., assignor
to William Sellers & Company Incorporated,
Philadelphia, Pa., a corporation of Pennsyl-
vania

Application January 18, 1933. Serial No. 652,333

4 Claims. (Cl. 122—504)

This invention relates to a safety connection between a water column and a boiler designed to avoid boiler explosions or lesser damage occasioned by a falling of water level below a critical point which may not be noticed on a gauge attached to the water column or determinable by opening of the usual gauge cocks.

The invention relates particularly to the provision of a form of connecting nipple designed to prevent stopping of the connections between a boiler and a water column. The arrangement will be apparent from the following description read in conjunction with the accompanying drawing in which:

15 Fig. 1 is a fragmentary sectional view showing a boiler, a water column and the connections between the two; and

Fig. 2 is an enlarged sectional view through certain portions of the connections.

20 Referring first to Fig. 1, there is illustrated at 2 the top of a boiler shown in the present instance as a locomotive boiler while 4 indicates the crown sheet of the same. In a boiler of this type it is necessary for safety that the water level should 25 always be above the crown sheet. In order to give indication of this there is attached to the boiler the usual form of water column indicated at 6 provided with a plurality of gauge cocks indicated at 8, the uppermost and lowermost of which are above and below normal water level.

30 A gauge glass 10 is connected at its upper end with the water column through a gooseneck 12 and an upper valve 14. At its lower end the glass has connections with the water column through a valve 16. The lower end of the water column is connected to a water leg of the boiler through connection indicated at 18 while its upper end communicates with the steam space of the boiler through the conduit illustrated at 20.

40 Referring now more particularly to Fig. 2 the conduit 20, taking the form of a pipe, is threaded into a nipple 22 which is provided with a flange 24 resting upon an outwardly facing seat formed at the upper end of a union 26 threaded into the top wall of the boiler. A coupling nut 28 serves to clamp the flange 24 against the seat.

45 Heretofore the nipple 22 terminated at the level of the lowermost face of the flange 24. Considering the nipple of this old type, everything so far described constitutes the usual conventional structure.

50 The conventional structure is dangerous for the following reason which has resulted definitely in at least one boiler explosion resulting in the loss of a number of lives and great damage to prop-

erty. The danger arises in view of the fact that when the boiler is tested for its ability to withstand pressure the steam gauge connections are removed leaving in position, however, the union 26. In order to close this union a solid washer is 60 located on the seat thereof and clamped down against the seat by either the coupling nut such as 28 normally used for making the connection with the water column or a cap. These connections in a locomotive are normally at a fairly in- 65 accessible position and following a pressure test a careless workman is likely to remove the coupling nut or cap but may fail to remove the washer. He may then without noticing anything wrong place on top of the washer the nipple and 70 secure it in position by the clamping nut 28. When water is introduced into the boiler and steam generated since there is no outlet into the connection 20 the water will be forced from the water leg into the water column and up into the 75 pipe 20, compressing any air therein, so that visual indication given by the gauge glass and also the use of the trycocks will result in a conclusion that the boiler is full of water. As evaporation takes place and the water level drops, although 80 it may have at first been normal, the same conditions will remain the water column indicating a 85 full boiler. If eventually the crown sheet is uncovered a disastrous explosion may result.

The conditions just outlined were those determined as having existed in at least one instance.

In accordance with the present invention the usual nipple is modified by the provision of an extension 30 which may, as shown, take the form of a tube or may alternatively consist of one 90 or more prongs extending downwardly beyond the flange 24. The minimum length of this extension should be such that if a washer obstructed the free passage through the union at the level of the seat, the flange 24 would not move 95 downwardly sufficiently to permit the coupling nut to be engaged with the threads on the upper end of the union. Preferably, however, this extension is of greater length and may be of the length indicated in which it extends completely 100 through the union into the boiler. This would prevent any connection of the coupling nut which might appear to be satisfactory as long as any obstruction existed within the union 26 since a washer or the like might possibly be forced downwardly below the seat but would still be held frictionally within the bore of the union and be jammed into a stoppage position by the pressure of steam. It will be obvious that the construction described insures the non-occurrence of the 105 110

conditions outlined above which are likely to cause an explosion.

Instead of having the safety extension 30 secured to the nipple 22 it may form an extension 6 of the pipe 20 and as indicated above may take the form of either a complete cylindrical extension of the pipe or one or more prongs extending either beyond the seat of the union 26 or within the boiler.

10 What I claim and desire to protect by Letters Patent is:

1. In combination, a boiler, a water column, and upper and lower connections between the water column and the boiler, said upper connections including a union adjacent the boiler provided with an outwardly facing seat, a nipple having a flange, and a coupling nut threaded on said union and arranged to clamp the flange of the nipple upon said seat, said connections including a safety extension projecting within the union inwardly of said seat when the parts are assembled.

2. In combination, a boiler, a water column, and upper and lower connections between the water column and the boiler, said upper connections including a union threaded into the boiler 25 provided with an outwardly facing seat, a nipple

having a flange, and a coupling nut threaded on said union and arranged to clamp the flange of the nipple upon said seat, said connections including a safety extension projecting through the union into the boiler when the parts are assembled. 80

3. In combination, a boiler, a water column, and upper and lower connections between the water column and the boiler, said upper connections including a union adjacent the boiler provided with an outwardly facing seat, a nipple 85 having a flange, and a coupling nut threaded on said union and arranged to clamp the flange of the nipple upon said seat, said nipple having a safety extension projecting within the union 90

95

4. In combination, a boiler, a water column, and upper and lower connections between the water column and the boiler, said upper connections including a union threaded into the boiler provided with an outwardly facing seat, a nipple having a flange, and a coupling nut threaded on said union and arranged to clamp the flange of the nipple upon said seat, said nipple having a safety extension projecting through the union 100

into the boiler.
